UNITED STATES PATENT OFFICE.

THOMAS BERTON HOLDERNESS, OF DE KALB, ILLINOIS.

GAS-BURNER ATTACHMENT.

1,100,371.

Specification of Letters Patent. Patented June 16, 1914.

Application filed July 18, 1912. Serial No. 710,228.

To all whom it may concern:

Be it known that I, THOMAS BERTON HOLDERNESS, a citizen of the United States, residing at De Kalb, in the county of Dekalb and State of Illinois, have invented certain new and useful Improvements in Gas-Burner Attachments; and I do hereby declare the following to be a full, clear, and exact description of the invention, such as will enable others skilled in the art to which it appertains to make and use the same.

My invention relates to gas, gasoline and other forms of stoves, and more particularly to an attachment designed for saving heat or utilizing the same to the fullest possible extent, and my object therefore is to provide means which will accomplish a maximum amount of heating with the use of a minimum amount of fuel.

20 A further object of my invention is to provide improved means whereby the heat from a single burner will be directed for the purpose of heating two separate and distinct vessels.

25 Other objects and advantages will be hereinafter made clearly apparent, reference being had to the accompanying drawings which are made a part of this application and in which—

30 Figure 1 shows a perspective view of my invention complete, ready for use upon a gas or gasoline or other form of stove. Fig. 2 is a longitudinal sectional view. Fig. 3 is a transverse section on the line 3—3 of Fig. 35 1. Fig. 4 is a perspective detail view of a special form of lid designed for one of the burners, and, Fig. 5 shows in perspective the ring-like members.

In order to conveniently refer to the various parts of my invention, numerals will be employed, and referring to the numerals on the drawings, 1 and 2 indicate a pair of ring-like members, open at both their top and bottom sides and designed to fit directly over two adjacent burners of a gas, gasoline or other form of stove, said members 1 and 2 being formed with the connecting sections 3 and 4, which are left open on their ends and under sides but entirely closed upon their upper side, as clearly shown in Figs. 1, 2 and 3. I prefer to incline the walls of

the members 1 and 2, substantially as shown, and it is also important that the connecting members 3 be of sufficient length to dispose the ring-like members 1 and 2 directly over 55 pairs of burners at different distances apart upon the stove.

The members 3 and 4 are made telescopic, as shown in Fig. 5 whereby the ring-like members 1' and 2' may be moved toward or 60 away from each other, as desired, to insure that they may be properly located relative to the burners. Each of the ring-like members is provided with members 3 and 4, one of which is of sufficient size to nest within or 65 telescope the other, whereby the ring-like members 1' and 2' may be drawn away from each other or moved closer together as preferred. I also provide the cover section 5 of sufficient diameter to fit upon the top edge 70 of one of the members 1 and 2, the said cover section 5 being provided with an opening of proper size to accommodate smaller sized cooking vessels. The position shown by the lid section 5 is indicated by dotted lines in 75 Fig. 2. Upon the edge of one of the ring-like members 1 and 2, as indicated by the numeral 6, I provide a plurality of recesses or notches, said recesses being designed to facilitate the escape of heat after it has 80 passed upward in contact with the bottom of the vessel sitting over the ring-like member 1 and has thence passed through the member 3 into the ring-like member 2, engaging with the bottom of the vessel sitting 85 thereon, thence passing out of said recesses 6. It will thus be seen that I have provided thoroughly reliable and efficient means for conserving the amount of heat generated by one of the burners, whereby it will pass from 90 the burner surrounded by the member 1, through the connecting members 3 and 4, and thence out through the open end of the member 2 or through the recesses 6 if a vessel should be placed upon the said member 2. 95

What I claim is:—

A portable attachment for stove burners comprising downwardly diverging frusto-conical rings to fit over two adjacent burners, each ring having a portion of one side 100 removed, forming an opening, and a projection from said opening consisting of sides

and top, said projections being adapted to telescope one on the other to form an open unobstructed passage from one ring to the other, adjustable in length to adapt the device for use on adjacent burners at different distances apart.

In testimony whereof I have signed my

name to this specification in the presence of two subscribing witnesses.

THOMAS BERTON HOLDERNESS.
